UNITED STATES PATENT OFFICE.

ALFRED KÜRTH, OF BERLIN, GERMANY.

WINDOW-OPENING DEVICE.

Application filed February 11, 1920. Serial No. 358,010.

(GRANTED UNDER THE PROVISIONS OF THE ACT OF MARCH 3, 1921, 41 STAT. L., 1313.)

To all whom it may concern:

Be it known that I, ALFRED KÜRTH, residing at 43 Kaiserallee, Wilmersdorf, Berlin, Germany, have invented certain new and useful Improvements in Window-Opening Devices, (for which I have filed applications in Germany on the 25th October, 1913, and 5th of July, 1916; Austria and Hungary on the 9th of September, 1914; Italy on the 21st of September, 1914; and France on the 22nd of October, 1914, French Patent No. 502,315, delivered February 19, 1920,) and of which the following is a specification.

This invention relates in general to devices
15 for opening windows by means of a lever
manipulated by the hand, and more par-
ticularly to such devices in railway car-
riages.

In a known form of device for opening carriage windows a handle or lever is provided beneath the window frame, which, on being pulled or pressed back, pushes a pressure frame—i. e. a frame that is pressed against the window by a spring, and thus keeps the window in position away from the window frame so as to release it. The window can now be moved as long as the said handle and the pressure frame affected by it remain in the position into which they have been moved. On the handle being returned to its initial position the pressure frame is again pressed by its spring against the window and this is then retained in the particular position it occupies at that moment.

These devices have a disadvantage which causes great inconvenience. To be able to move the window it is necessary to hold the handle with one hand, so that the other hand only can be used for moving the window. This is particularly disadvantageous in the cases of windows, which, like those usually provided in railway carriages, have their weights balanced in such a manner that, on the pressure frame being pulled away from a fully closed window, this latter immediately drops about 8 to 12 inches, whence, if it is to be opened further, it is pushed down directly by hand. When closing windows of this type the strength required in pushing them up through the said top 8 to 12 inches is by no means small, and it will often happen that the one arm, especially of a lady or child, will not be

strong enough for the purpose. The second 55 arm is, however, not available because the handle has to be held in its moved position if the window is to be at all movable.

To remove this drawback contrivances have been proposed by which the handle, after it has been moved for the purpose of pulling back the pressure frame from the window, is retained in its moved position so that it may be let go without the pressure frame again pressing against the window and both hands may be used for shifting the window. But the gain achieved by this is not very great because it is still necessary to hold the raised window in its highest position with one hand whilst restoring the handle to its normal position.

An object of the invention is to remove this drawback and this is accomplished by providing means by which the handle is automatically restored to its normal position the moment the window reaches its uppermost position. 75

Another feature of the above described devices for opening windows consists in means for lifting the window off the rain 80 or splash board when the pressure frame is pulled or pushed back by pressure or pull exerted on the said handle. For this purpose seizing members or hooks, attached to the pressure frame and each having a bent 85 portion that passes round to the back of the window sash so as to loosely embrace it, are provided which seize this frame and disengage it from the splash board when the pressure frame is pushed back by the said han- 90

sure frame is passed away from the handle. The spring which presses the pressure frame against the window and the handle may both be arranged at about the same height and on the middle vertical line of the window and in such a manner that when 95 the pressure frame is forced away from the window by the said handle the spring is pressed together. This arrangement is unsuitable for very wide windows because, on account of the force which moves the 100 pressure frame away from the window being applied at one point only, this frame is liable to swerve round on its middle vertical axis. For this reason two springs, one at either side of the 105 pressure frame, are used in the case of wide windows for urging the pressure frame against the window and keeping it in a

parallel position when it is worked by the said handle. But a disadvantage resulting from this arrangement is that the force applied through the handle to the middle of the frame, in the opposite direction to the force of the two springs, bends the frame to such an extent that the two hooks at the sides of the frame cannot shift the window back far enough to separate it from the splash board. Another disadvantage of this known arrangement is that the pressure frame cannot be removed unless the window is first lifted out because the frame is connected to the window by the said hooks.

15 To remove these evils is another of the objects of this invention and this is accomplished by arranging the hooks, that are intended to shift the window off the splash board when the pressure frame is pulled back, to move in slotted guides attached to the frame instead of fixing them immovably to the frame. The hooks are adapted to move in the slots of the said guides in the same direction as the pressure frame and 20 are made subject to the action of springs that tend to press them against the window and shift it off the splash board when the pressure frame is pulled back.

25 Hitherto the pressure frame for the window with which the lock or the window opening device cooperates has usually been made and fitted into the carriage door by the carriage builders and it was frequently found on putting in the window opening device that the pressure frame did not properly conform to the parts of the device and had to be adapted to it. Another object of the invention is to remove this drawback and this is accomplished by mounting the 30 pressure frame and the window opening device or lock upon a common plate. This plate with all of the said parts then forms a complete apparatus and is mounted on and serves to strengthen the board which forms 35 the inner side of the window shaft or well into which the window sinks when let down. Since the window opening device and the pressure frame are mounted on a common plate the trouble which was frequently 40 caused by the distance between the frame and the said device being incorrect cannot 45 arise.

The invention is illustrated in the drawings in which

50 Fig. 1 is a vertical section through a window opening device in a closed window, i. e., a window that is pulled into its uppermost position.

55 Fig. 2 is a vertical section shewing the window in a position in which it can be moved up or down at will without working the handle, and

60 Fig. 3 is a section through Fig. 1 on the line A—B.

65 Fig. 4 is a vertical section through a wide

window provided with hooks that slide in guide members attached to the sides of the pressure frame, instead of fixed hooks as in the case of Figs. 1 and 2, which represent a design that is suitable for narrow windows.

70 Fig. 5 is a section through Fig. 4 on the line a—b, and

75 Fig. 6 is a section through Fig. 4 on the line c—d.

Fig. 7 is a vertical section through the part of a window equipped with a lock or window opening device with which the pressure frame is combined and in which special window seizing means for moving the 80 window away from the splash-board are afforded.

Fig. 8 is a similar section to Fig. 7 and shews the window lowered from the splash-board.

85 Fig. 9 is a view of the window opening device and the pressure frame mounted on a common plate as seen from the back of the plate or from the right in Fig. 8.

90 Mounted in the wall of the carriage or in the door frame 1 is a handle 2 which, when it is moved in the direction of the arrow, shifts the pressure frame 3 away from the sash 5 of the window pane 6 in opposition to a spring 4. The pressure frame 3 is connected 95 to the window sash by hooks or seizing members 7 which loosely embrace the window sash 5. Hence the shifting away of the pressure frame 3 from the window causes the window sash to be pulled off the splash-board 8 so as to enable the sash to be moved vertically.

95 The handle 2 which turns on a pivot 9 is connected by a link 10 to the pressure lever 11. This lever rocks on a pivot 12, whilst the link 10 is joined at one 100 end by a pivot 13 to the handle 2 and at the other end by a pivot 14 to the said pressure lever 11. On the handle 2 being moved downwards as indicated by the arrow in Fig. 105 1 the pivot 13 is moved upwards on a circle 110 around the pivot 9 and the link 10 is moved forward (towards the window). Hence the pressure lever 11 is rocked in such a manner that its nose 15, which bears against a downwardly projecting rib 16 of the pressure 115 frame, pushes the pressure frame 3 away from the window whilst pressing together the spring 4. The result of these functions is that the handle and the link stretch out and the three pivots 9, 13 and 14 are brought 120 into line or into a line which curves slightly upwards (see Fig. 2). The handle 2 is hereby locked in its lower position so as to prevent its being moved by the pressure of the spring 4, and the window sash is then released and free to be moved.

125 On its now being raised to its uppermost position it is not immediately and automatically set onto the splash-board because the pressure frame is kept out of contact with it. The setting 130

of the window onto the splash-board would now either have to be performed by pressing the hand against the inside of the window—when the possibility would remain of 5 the window being shaken off the splash-board by vibration and falling down again on account of its not being secured in place by the action of the pressure frame—or it would be necessary, after pushing up the 10 window, to remove one hand from the window so as to be able to use it for moving the handle out of the locked position.

According to the invention the following arrangement is provided for removing this 15 drawback: Loosely mounted on the pivot 12 is a cam 19 which lies in the path of a dependent hook or curved piece 18, on the window sash. The cam 19 is provided with a sliding surface, which engages with a 20 surface 20 on the inner end of the handle 2 when this handle is moved into its locked position (see Fig. 2). The arrangement of the cam 19 and the hook 18 is such that the hook slightly lifts the cam at the nose 25 end 17 of the cam when the window in being closed reaches its highest position. The sliding surface of the cam will then be pressed against the surface 20 at the rear end of the handle 2. This will force the 30 pivot points 9, 13 and 14 from the position shown in Fig. 2 and, the pressure spring 4 bearing against the pressure frame 3, the handle 2 is turned back into its initial position (Fig. 1).

35 The hooks or window seizing members 7 shown in Figs. 1 and 2 are, as stated in preceding paragraphs, not eminently suitable for shifting the sashes of wide windows away from their splash boards. A preferred form of these members or hooks is 40 illustrated in Figs. 4 to 6 according to which they are not rigidly fixed to the pressure frame 3 but are arranged to slide in guide members 21 and 22 attached to the pressure frame. Fixed to each hook 7 is a spring 23 which abuts against the wall into which the window sash is fitted and tends to press the hook 7 against the window sash. But the hook is prevented from contacting with the 45 window sash while at rest by means of an extension 24 which bears at *a* against an overlapping portion 25 of the pressure frame, see Fig. 5.

On the pressure frame 3 being moved away 50 from the window by moving the lever 15 through pressure exerted on the handle 2 the two hooks situated at both sides of the window are caused by their springs 23 to participate in this movement and in so doing 55 they strike against the sash of the window 6 and shift the window off the splash-board. But the hooks only bear against the window frame until the extensions 24 of the hooks 7 again strike against the overlapping portions of the pressure frame at *a*, which will

happen when the pressure frame comes to rest. The springs will then no longer be able to press the hooks forward so that it will be possible to move the window with perfect freedom.

In the modification shown in Figs. 7 to 9 the arrangement is such, that the window opening device can be fitted into the wall or window much easier than the old types or than those hereinbefore described. This is 70 accomplished by arranging the pressure frame not so as to rock on pivots or hinges at the top of the window frame in the usual manner but on a metal plate on which all the parts of the window opening device such 75 as the handle 2', lever 11' etc. are also mounted. The entire contrivance including the pressure frame can then be supplied to the carriage builders complete and ready to be fixed by them in the wall of a carriage. 80

85 Stamped up out of a metal plate 26 (Figs. 7 to 9) so as to project upwardly from the same are ears 27 and arms 29 swing upon pivots 28 held in these ears. The arms 29 are connected to each other by a cross bar 90 3 which replaces the lower horizontal board of the pressure frame 3 of Figs. 1 to 3 and acts as a pressure frame. As in Figs. 1 to 3 this frame has a downwardly projecting rib 16 against which the lever 11' is pressed. 95 This lever 11', the handle 2', and its cooperating parts are mounted in a casing 30 which, like the arms 29, is fixed to two ears 31 which are stamped up out of the plate 26.

The means for shifting the window off 100 the splash-board when the pressure frame is moved back consists in this case merely of a spring 32 which exerts constant pressure against the border 5 of the window sash instead of the hooks 7 or 7' previously described.

105 It will be evident that many changes and modifications of the described details may be made without departing from the spirit of the invention, or exceeding the scope of 110 the appended claims.

I claim:

1. The combination of a window sash arranged for opening and closing by sliding movement, a movable pressure member engageable with said sash and bearing against the sash when the same is closed; means for imparting movement to the pressure member; a movable operating handle; and means cooperating, with the first mentioned means 115 and with said operating handle for moving said pressure member away from said sash to permit sliding movement of the sash, and for locking the operating handle in the position to which it is moved.

120 2. The combination, of a window sash arranged for opening and closing by sliding movement; a movable pressure member engageable with said sash and bearing against the sash when the same is closed; a movable 130

- operating handle; means for imparting movement to the pressure member, means cooperating with the first mentioned means and with said operating handle for moving said pressure member away from said sash to permit sliding movement of the sash and for locking the operating handle in the position to which it is moved; and means cooperating with said sash and with said operating handle for unlocking the handle when the sash is moved to closing position.
3. The combination, of a window sash arranged for opening and closing by sliding movement; a movable pressure member engageable with said sash and bearing against the sash when the same is closed; means for imparting movement to the pressure member; a movable operating handle; means cooperating with the first mentioned means and with said operating handle for moving said pressure member away from said sash to permit sliding movement of the sash and for locking the operating handle in the position to which it is moved; and means cooperating with said sash and with said operating handle for unlocking the operating handle and to permit the same to be returned to its initial position when the sash is moved to closing position.
4. The combination, with a window frame having a splash board, of a window sash in said window frame arranged for opening and closing by sliding movement and engaging said splash board when closed; a movable pressure member engageable with said sash and bearing against the sash to retain the same on said splash board when the sash is closed; means for imparting movement to the pressure member; means for shifting the sash off said splash board when the pressure member is moved away from said sash; a movable operating handle; and means cooperating with the first mentioned means and with said operating handle for moving said pressure member away from said sash to permit sliding movement of the sash and for locking the operating handle in the position to which it is moved.
5. The combination, with a window frame having a splash board, of a window sash in said frame arranged for opening and closing by sliding movement and engaging said splash board when closed; a movable pressure member engageable with said sash and bearing against the sash to retain the same on said splash board when the sash is closed; a movable operating handle; means for imparting movement to the pressure member; means for shifting the sash off said splash board when the pressure member is moved away from said sash and permitting return by the pressure member of the sash to position on the splash board when the sash is moved to closed position; means cooperating with the first mentioned means and with

said operating handle for moving said pressure member away from said sash and said sash off the splash board to permit sliding movement of the sash, and for locking the operating handle in the position to which it is moved; and means cooperating, when the sash is moved to closing position, with said sash and with said operating handle for unlocking the operating handle.

6. The combination, with a window frame having a splash board, of a window sash in said frame arranged for opening and closing by sliding movement and engaging said splash board when closed; a movable pressure member engageable with said sash and bearing against the sash to retain the same on said splash board; a movable operating handle; means for imparting movement to the pressure member; means for shifting the sash off said splash board when the pressure member is moved away from said sash and permitting return by the pressure member of the sash to position on the splash board when the sash is moved to closed position; means cooperating with the first mentioned means and with said operating handle for moving said pressure member away from said sash and said sash off the splash board to permit sliding movement of the sash, and for locking the operating handle in the position to which it is moved; and means cooperating, when the sash is moved to closing position, with said sash and with said operating handle for unlocking the operating handle to permit the same to be returned to its initial position.

7. The combination, of a window sash arranged for opening and closing by sliding movement; a movable pressure member engageable with said sash and bearing against the sash when the same is closed; lever means for moving the pressure member away from said sash to permit sliding movement thereof; a movable operating handle; and link means operatively connected to said lever means and to said handle, whereby when said handle is moved in one direction said pressure member is moved away from said sash and said handle is locked in the position to which it is moved.

8. The combination, of a window sash arranged for opening and closing by sliding movement; a movable pressure member engageable with said sash and bearing against the sash when the same is closed; lever means for moving the pressure member away from said sash to permit sliding movement thereof; a movable operating handle; link means operatively connected to said lever means and to said handle, whereby when said handle is moved in one direction said pressure member is moved away from said sash and said handle is locked in the position to which it is moved; dependent means carried by and movable with the window sash;

and means provided with a face for engaging said handle and an end engageable with the dependent means of said sash when the sash is moved to closing position, whereby, 5 when said sash is moved to closing position, said handle is unlocked and returned to its initial position.

9. The combination, with a window frame having a splash board, of a window sash in 10 said frame arranged for opening and closing by sliding movement and engaging said splash board when closed; a spring actuated pressure member engageable with said sash and bearing against the sash to retain the 15 same on the splash board; a movable operating handle; lever means for moving the pressure member away from said sash to permit sliding movement thereof; hook means appurtenant to said pressure member and 20 engageable with said sash for shifting the sash off said splash board when the pressure member is moved away from said sash; and link means cooperating with said lever means and with said handle for moving said 25 pressure member away from said sash and said sash off said splash board, and for locking the operating handle in the position to which it is moved.

10. The combination, with a window 30 frame having a splash board, of a window sash in said frame arranged for opening and closing by sliding movement and engaging

said splash board when closed; a spring actuated pressure member engageable with said sash and bearing against the sash to 35 retain the same on the splash board; a movable operating handle; lever means for moving the pressure member away from said sash to permit sliding movement thereof; hook means appurtenant to said pressure member and engageable with said sash for shifting the sash off said splash board when the pressure member is moved away from said sash, and permitting return by the 40 spring actuated pressure member of the sash 45 to position on the splash board when the sash is moved to closed position; link means cooperating with said lever means and with said handle for moving said pressure member away from said sash and said sash off 50 said splash board and for locking the operating handle in the position to which it is moved; dependent hook means carried by and movable with said sash; and means provided with a cam face for engaging said handle and a nose end engageable with said dependent hook of the sash when the sash is moved to closing position, for unlocking 55 the operating handle and to permit the same to be returned to its initial position. 60

In testimony whereof I have signed this specification.

DR. ALFRED KÜRTH.
